US00D648730S

(12) **United States Design Patent**
Huang

(10) **Patent No.:** **US D648,730 S**
(45) **Date of Patent:** **** Nov. 15, 2011**

(54) **USB DONGLE**

(75) Inventor: **Chih-Hua Huang**, Shulin (TW)

(73) Assignee: **Askey Computer Corp.** (TW)

(**) Term: **14 Years**

(21) Appl. No.: **29/380,135**

(22) Filed: **Dec. 1, 2010**

(30) **Foreign Application Priority Data**

Oct. 29, 2010 (TW) 99305551

(51) **LOC (9) Cl.** **14-02**

(52) **U.S. Cl.** **D14/480.5**

(58) **Field of Classification Search** D14/411,
D14/433, 435.1, 436, 480.1–480.7, 484.1,
